UNITED STATES PATENT OFFICE.

FORREST T. DURNER, OF EVANSVILLE, WISCONSIN.

LATCH.

1,058,952.

Specification of Letters Patent.

Patented Apr. 15, 1913.

Application filed September 23, 1912. Serial No. 721,895.

To all whom it may concern:

Be it known that I, FORREST T. DURNER, a citizen of the United States, residing at Evansville, in the county of Rock and State 5 of Wisconsin, have invented a new and useful Latch, of which the following is a specification.

The present invention relates to improvements in latches, the primary object of the 10 invention being the provision of a latch having two independently actuated spring projected locking bars, so positioned that the two may be retracted simultaneously, yet independently of each other, rendering the 15 necessity of retracting both at the same time to unlock the latch, the particular latch being especially adapted for fastening cupboard doors, gates or doors to private offices and the like.

20 A further object of the present invention is the provision of a latch having two independently actuated and parallel locking members, each one of which is provided with a handle, said handles of the two locking 25 members projecting in opposite directions but in ready access to the operator, so that both locking members may be retracted by the spanning of the casing with the hand so that the thumb and a finger may manipulate 30 the members, the unlocking of the latch requiring the retraction simultaneously of both members.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed can be made within the scope of what is claimed without departing from the spirit of the invention.

In the drawings—Figure 1 is a sectional view through the casing of the latch showing 45 the two locking members in locking position. Fig. 2 is a top plan view of the locking member carrying casing.

Referring to the drawings, the numeral 1 designates the base which carries the casing 50 2, said casing 2 being provided with the oppositely disposed elongated slot 3 and with the rectangular slot 4, the purposes of which will presently appear.

Connected to the wall of the casing at the 55 opposite end to the slot 4 are the two pins 5—5', which have disposed thereupon the

respective springs 6—6'. These springs abut the rear ends respectively of the locking members 7—7', and normally hold the same in locking position, with the shouldered 60 portions 8—8^a abutting the stop pins 9—9^a, the shouldered portions 8'—8^b being disposed to engage pins 9'—9^b when the locking members are retracted against the springs 6—6', and when the respective pins 65 5—5' are seated within the elongated sockets 10—10' of the locking members. Each locking member is provided with its respective handle 11 having the knob 12, each handle 11 being projected through its respective aperture 3 or 3' of the casing 2, said casing 2 being of such a width as to permit of the engagement of the respective handles by the thumb and one finger of the same hand of an operator so that the locking members 70 75 may be retracted simultaneously against the springs and to disengage the catch engaging ends 13—13' from the casing 14 of the catch plate 15.

From the foregoing description, taken in 80 connection with the drawings it is evident that with a lock or latch constructed according to the present invention, that in order to release the latch so that the door controlled thereby may be opened, that both locking 85 members must be retracted simultaneously so that the engaging ends 13—13' are withdrawn within the casing 2 and against the tension of both springs 6—6'. The manipulation of either one will not effect the disengagement of the latch, thus rendering the 90 liability of tampering with the latch in releasing the same more difficult.

This form of latch is especially useful in 95 connection with locks upon cupboards or the like, that may be tampered with by small children, one of the locking members remaining in closed or locking position at all times and necessitating, as before set forth, the simultaneous operation of both of 100 the independent members before the door can be opened.

The aperture 4, pins 5—5', and the pins 9, 9', 9^a and 9^b all co-act to provide guiding means for retaining the locking members in 105 parallel and properly within the casing 2 and at the same time the four last mentioned pins provide means for limiting the retraction and projection of the locking members within the casing.

What is claimed is:

1. A latch, including a casing having op-

positely disposed elongated apertures, two spring projected locking members mounted in the casing, and a handle for each member projecting exteriorly of the casing through 5 the respective apertures thereof.

2. A latch, including a casing, two locking members mounted therein for independent movement, a spring to each member for holding the member projected, a handle for 10 each member to manually retract the member, and two spaced pins within the casing and to each member, one upon each side of the handle, for limiting the movement of each locking member.

15 3. A latch, including a casing provided with oppositely disposed elongated apertures, two locking members mounted within the casing for independent movement, a spring to each member for holding the member projected, a handle for each member projected through its respective elongated slot of the casing for manually retracting the members, and co-acting means carried by the locking members and the casing for 20 limiting the respective movements of the members.

4. A latch, including a casing provided with oppositely disposed elongated apertures, two locking members mounted within 30 the casing for independent movement, a spring to each member for holding the member projected, a handle for each member projected through its respective elongated slot of the casing for manually retracting its 35 member, and two spaced pins to each member within the casing, one upon each side of the handle for limiting the movement of its member.

5. A latch, including a casing provided 40 with oppositely disposed elongated aper-

tures, two longitudinally movable and parallel locking members mounted within the casing, the rear ends of said members being provided with sockets, a pin disposed within the casing and in alinement with each 45 socket of the locking members, a spring upon each pin for normally projecting its respective locking member, a handle for each locking member projected through its respective elongated slot of the casing for 50 manually retracting the locking member, and co-acting means carried by the respective locking members and the casing for limiting the longitudinal movement of the locking members.

55 6. A latch, including a casing provided with oppositely disposed elongated apertures, two longitudinally movable and parallel locking members mounted within the casing, the rear ends of said members each 50 being provided with a socket, a pin disposed within the casing and in alinement with each socket of the locking members, a spring upon each pin for normally projecting its respective locking member, a handle for 55 each locking member projected through its respective elongated slot of the casing for manually retracting the locking member, and two pins to each locking member one upon each side of its respective handle for 60 limiting the longitudinal movement of its locking member.

In testimony that I claim the foregoing as my own, I have hereto affixed my signature in the presence of two witnesses.

FORREST T. DURNER.
